US00D608739S

(12) **United States Design Patent**
Hussell

(10) **Patent No.:** **US D608,739 S**
(45) **Date of Patent:** ** *Jan. 26, 2010

(54) LED	6,841,931 B2	1/2005	Takahashi et al.
(75) Inventor: Christopher P. Hussell , Cary, NC (US)			(Continued)
(73) Assignee: Cree, Inc. , Durham, NC (US)			FOREIGN PATENT DOCUMENTS
(**) Term: 14 Years	JP	1066644	1/2000
(21) Appl. No.: 29/306,991			(Continued)
(22) Filed: Apr. 21, 2008			OTHER PUBLICATIONS
(51) LOC (9) Cl. 13-03			Nichia Press Release, "Summary of Patent Infringement Assessment Report," http://www.nichia.co.jp/about_nichia/2006/2006_021702.html , May 27, 2008 (3 sheets).
(52) U.S. Cl. D13/180			(Continued)
(58) Field of Classification Search D13/180; D26/2; 257/79, 80, 81, 88, 89, 95, 98, 99, 257/100; 313/483, 498, 500; 362/555, 800			<i>Primary Examiner</i> —Selina Sikder
See application file for complete search history.			(74) <i>Attorney, Agent, or Firm</i> —Myers Bigel Sibley & Sajovec
(56) References Cited			CLAIM
U.S. PATENT DOCUMENTS			The ornamental design for an LED, as shown and described.
D478,877 S 8/2003 Hoshiba			DESCRIPTION
D482,337 S 11/2003 Kamada			FIG. 1 is a front perspective view of an LED showing my design;
D489,677 S 5/2004 Ishida			FIG. 2 is a front view thereof;
D489,690 S 5/2004 Ishida			FIG. 3 is a bottom view thereof;
D489,691 S 5/2004 Ishida			FIG. 4 is an opposing top view thereof;
D489,692 S 5/2004 Ishida			FIG. 5 is a back view thereof opposite the view of FIG. 2;
D489,693 S 5/2004 Ishida			FIG. 6 is side view thereof;
D490,062 S 5/2004 Ishida			FIG. 7 is an opposing side view thereof; and,
D490,384 S 5/2004 Ishida			FIG. 8 is a back perspective view thereof.
D490,385 S 5/2004 Ishida			The broken lines shown herein are for illustrative purposes only and form no part of the claimed design. The illustrated device is not limited to the scale shown.
D490,386 S 5/2004 Ishida			
D490,783 S 6/2004 Ishida			
D490,784 S 6/2004 Ishida			
D491,538 S 6/2004 Ishida			
D493,429 S 7/2004 Ishida			
D495,667 S 9/2004 Kim et al.			
D496,007 S 9/2004 Hoshiba			
D497,349 S 10/2004 Hoshiba			
6,800,996 B2 10/2004 Nagai et al.			
D499,384 S 12/2004 Kamada			
D499,385 S 12/2004 Ishida			
D500,292 S 12/2004 Ishida			
D500,293 S 12/2004 Ishida			
D500,294 S 12/2004 Ishida
